EARTH ROLLER

Noah Ellsworth Welford, Norman, Okla.

Application November 27, 1939, Serial No. 306,351

3 Claims. (Cl. 94—50)

This invention relates to an improvement in earth rolling and packing devices.

It is the chief object of the invention to provide a device of this class which will compact earth, crushed stone, gravel, and numerous other materials of construction in their natural or artificial combination, or in combination with other industrial products, without causing "bridging" of the material being compacted. It is particularly efficient in the construction of roads, dams, levees, airport runways and the like. It is so constructed that it exerts a rolling-shifting action on the material being compacted, thus practically eliminating voids in freshly laid material.

The details in the construction of a preferred form of my invention, together with other objects attending its production, will be better understood from the following description when read in connection with the accompanying drawing, which is chosen for illustrative purposes only, and in which,

Figure 1 is an oblique view of a preferred embodiment of the invention;

Figure 2 is an end view of a scraper, which is a part of the embodiment illustrated in Figure 1; and

Figure 3 is a plan view of two of my earth rollers hooked in tandem with other earth compacting devices, and illustrates particularly a preferred manner of using my invention.

The embodiment illustrated includes a roller, designated as a whole by the letter A, and made up of a cylinder, preferably hollow, which rigidly carries on its exterior surface multiple helical ribs *a* of suitable rise and face width, the troughs between the ribs being of hyperbolic or other conic cross-sectional shape to reduce clogging of material between the ribs to a minimum by inducing a slight lateral and oblique shift of the material as it enters the troughs. As this roller travels over the surface of the material being compacted, its helical ribs will form a pattern of parallel compaction lines which lie at an angle to the direction of travel of the roller, and two such rollers, having their ribs running in opposite directions as illustrated in Figure 3, will form a diamond shaped pattern with the points of the diamonds in substantial alignment with the direction of travel.

The respective ends of the cylinder are preferably milled and closed tightly by cylinder heads B, which may be held rigidly in position by stud bolts, as shown, or by other suitable means. Water, sand, or other material may thus be

placed within the cylinder to increase the weight of the roller if desired.

One cylinder head B carries a sprocket, as shown clearly in Figure 1, for driving a scraper C. Both cylinder heads B carry aligned bearing axles D which respectively support and are journaled in opposite sides of a suitable rigid main frame E, which frame also serves to journal the opposite ends of a scraper C in bearings H, and

10 also serves as a means by which the roller A is pulled over the ground.

The scraper C consists of a shaft on which a plurality of radially projecting prongs *c* are carried in helical arrangement. One end of this 15 shaft also carries a second and smaller sprocket G of such diameter with relation to the first mentioned sprocket, that when the two are operably connected together by a chain, as shown in Figure 1, and the roller A is pulled over the 20 ground, the scraper shaft will be rotated at such a speed that the prongs *c* will mesh with the helical ribs *a* on the roller. Prongs are preferably positioned to present the pattern of a right cross, as shown by the end view in Figure 2. In cross section the prongs *c* are preferably but not necessarily hyperbolic.

While I have described and illustrated a specific embodiment of my invention I am aware that it may be embodied in other forms and I do not wish to be limited except by the prior art and by the scope of the appended claims.

I claim:

1. An earth compacting device comprising: a frame; a roller journaled in said frame; helical ribs on the surface of said roller; a scraper rotatably mounted on said frame parallel with said roller; a plurality of outwardly projecting prongs helically arranged on said scraper and adapted to intermesh with the ribs on said roller as it travels along the ground; and driving means operably connecting said roller with said scraper in such ratio that the prongs of the scraper will mesh with the ribs of the roller as the roller travels along the ground, the prongs of the scraper thus cleaning the space between the ribs of the roller.

2. An earth compacting device comprising: a cylindrical roller having a plurality of spaced ribs extending around its rolling surface; a scraper 50 axle having a plurality of similarly spaced outwardly projecting prongs thereon; a frame in which said roller and said scraper axle are rotatably mounted with their rotational axes in parallel relation and in such proximity that said prongs mesh between said ribs; and driving

means operably connecting said roller with said scraper axle for driving the latter as the former is rotated.

3. An earth compacting device comprising: a cylindrical roller having a plurality of spaced ribs extending around its rolling surface; a scraper axle having a plurality of similarly spaced outwardly projecting prongs thereon; a frame in which said roller and said scraper are rotatably

5 mounted with their rotational axes in parallel relation and in such proximity that said prongs mesh between said ribs; driving means operably connecting said roller with said scraper axle for driving the latter as the former is rotated; and a hitch connected to said frame for propelling the device.

NOAH ELLSWORTH WOLFARD.
